UNITED STATES PATENT OFFICE

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed April 22, 1931. Serial No. 532,025.

My invention relates to railway traffic controlling apparatus, and particularly to apparatus of the type involving a railway switch, a manually operable lever for the control of the switch, and indication apparatus controlled by the switch for governing the operation of the lever.

I will describe two forms of railway traffic controlling apparatus embodying my invention, and will then point out the novel features thereof in claims.

In the accompanying drawings, Fig. 1 is a diagrammatic view illustrating one form of railway traffic controlling apparatus embodying my invention. Fig. 2 is a view showing a modified form of a portion of the apparatus illustrated in Fig. 1, and also embodying my invention.

Referring first to Fig. 1, the reference character A designates a railway switch which is operated by a switch mechanism E. As here shown, the switch mechanism E is of the direct-acting electropneumatic type provided with a normal magnet G, and a reverse magnet Q, but this particular form of switch mechanism is not essential to my invention. The structure of the switch mechanism E forms no part of my present invention, and for purposes of the present disclosure, it is sufficient to say that the switch will be moved to its normal or its reverse position according as the normal magnet G or the reverse magnet Q is energized. One form of switch mechanism which will operate in the manner set forth is shown and described in Letters Patent of the United States No. 1,392,737, granted to C. R. Beall on October 4, 1921.

The mechanism E is controlled by a manually operable lever L, which may be one of a number of similar levers in an interlocking machine located at a point remote from the switch, such for example, as in an interlocking cabin. Lever L is capable of assuming a plurality of different positions, indicated by broken lines in the drawings, and designated by the reference characters N, B, D and R, respectively. Associated with lever L are a plurality of contacts 1, 2, 3, 4, 5 and 6, adjacent each of which is a letter or

letters which correspond to the lever positions for which the corresponding contact is closed. For example, contact 6 is closed only when lever L is in its D position. Similarly, contact 2 is closed when lever L is in its D position, its R position, or any position intermediate these two.

Attached to the lever L is a locking segment 7 which cooperates with a latch 8 operated by a lock magnet 9. As shown in the drawings, the lever is in its N position. If the operator attempts to move the lever toward its R position, a projection 7^a on the underside of segment 7 will engage the latch 8 and prevent movement of the lever to its D position unless the lock magnet 9 is deenergized. If the magnet is deenergized to permit the projection 7^a to pass the latch, the magnet must be subsequently energized to lift the latch out of engagement with the shoulder 7^b to permit the lever to move to its full reverse position. In similar manner, when the lever is moved from the R to its N position, the lock magnet 9 must be deenergized to permit the projection 7^a to pass the latch 8 to allow the lever to assume its B position, and must again be energized to permit the shoulder 7^b to pass the latch 8 to allow the lever to move to its normal position.

The lock magnet 9 is controlled in part by the usual polarized indication relay K which, as here shown, is supplied with energy from a pair of wires or bus bars 10 and 11 over a pole-changer P operated by switch A. The bus bars 10 and 11 may be supplied with current from any suitable source. As here shown, the bus bars are connected with the secondary 26 of a transformer T through a full wave rectifier F of the well-known copper oxide variety. The primary 27 of transformer T is constantly supplied with alternating current from the terminals X and Y of a suitable source not shown in the drawing. The parts are so arranged that when the switch A occupies its normal position in which it is shown in the drawings, relay K is energized in its normal direction so that its normal contact 12-12^a is closed. When the switch is reversed, however, the consequent reversal of pole-changer P causes relay K

100

to be energized in its reverse direction, so that its reverse contact 12-12^b becomes closed.

Lock magnet 9 is provided with a circuit which passes from bus bar 10 through wire 13, front contact 14 of relay K, wire 15, normal contact 12-12^a of relay K, wire 16, contact 5 of lever L, wires 17 and 18, winding of magnet 9, and wire 19 to bus bar 11. Lock magnet 9 is also provided with a circuit which passes from bus bar 10, through wire 13, front contact 14 of relay K, wire 15, reverse contact 12-12^b of relay K, wire 20, contact 6 of lever L, wire 18, winding of magnet 9, and wire 19 to bus bar 11. It will be apparent, therefore, that magnet 9 will be energized when lever L is in its B position provided relay K is energized in its normal direction, or when lever L is in its D position provided relay K is energized in its reverse direction.

The normal magnet G of mechanism E is provided with a circuit which may be traced from bus bar 10 through wires 21 and 22, contact 1 of lever L in any position between N and B, both inclusive, line wire 23, winding of magnet G, and common line wire 24 to bus bar 11. When this circuit is closed, normal magnet G is energized, and the switch is moved to its normal position in which it is illustrated in the drawings. The reverse magnet Q of mechanism E is likewise provided with a circuit which may be traced from bus bar 10 through wire 21, contact 2 of lever L in any position between D and R, both inclusive, line wire 25 winding of magnet Q, and common line wire 24 to bus bar 11. When this circuit is closed, reverse magnet Q is energized, and the switch A is moved to its reverse position.

The apparatus thus far described is all well known, and its operation is as follows: Assuming that the parts are in the positions in which they are illustrated in the drawings, if the operator wishes to move switch A from its normal position to its reverse position, he moves lever L from its N position toward its R position. During this movement when the lever reaches its B position, contact 5 becomes closed, and completes the circuit previously traced for lock magnet 9 including this contact, so that lock magnet 9 becomes energized; but, as soon as the lever passes its B position, contact 5 opens and interrupts the circuit for magnet 9, so that magnet 9 again becomes deenergized, thus permitting the projection 7^a on the locking segment 7 to pass the latch 8 under these conditions. Furthermore, as soon as the lever passes its B position, contact 1 becomes opened and interrupts the circuit previously traced for magnet G, so that magnet G becomes deenergized. When the lever reaches its D position, further movement of the lever is prevented by engagement of the latch 8 with the

shoulder 7^b. In this position of the lever, however, contact 2 is closed, and the circuit for magnet Q is completed, so that magnet Q becomes energized. Mechanism E therefore operates to move switch A from its normal to its reverse position. As soon as switch A starts to move, the circuit which was previously closed for relay K becomes opened at pole changer P. Relay K therefore becomes deenergized and subsequently remains deenergized until the switch reaches its full reverse position, at which time, the subsequent reversal of pole changer P causes relay K to become energized in its reverse direction. When relay K becomes energized in its reverse direction, it opens its normal contact 12-12^a and closes its reverse contact 12-12^b. Since contact 6 of lever L is then closed, the closing of reverse contact 12-12^b of relay K completes the circuit previously traced for lock magnet 9, and magnet 9 therefore becomes energized. This lifts the latch 8, so that the movement of the lever to its full reverse position can now be completed. When this has been done, contact 6 becomes opened and lock magnet 9 again becomes deenergized.

When the switch occupies its reverse position and it is desired to restore the switch to its normal position, the operator moves lever L from its R position toward its N position. The operation of the apparatus during this movement is substantially the reverse of that just described, and will be readily understood from an inspection of the drawings without describing it in detail.

Associated with the apparatus thus far described is indication apparatus embodying my invention, which indication apparatus, I will now describe.

As here shown, this indication apparatus comprises a suitable indication device, illustrated for convenience as a lever light 34, which light is controlled by the lever L, by the indication relay K, and by a power-off relay C. As here shown, lever light 34 is provided with a circuit which is closed only when relay C is energized, when relay K is deenergized, and when contact 4 of lever L is closed, this circuit passing from bus bar 10 through wire 35, front contact 36 of relay C, wire 37, filament of lever light 34, wires 38 and 39, back contact 40 of relay K, wire 41, contact 4 of lever L, and wires 42 and 43 to bus bar 11. Lever light 34 is also provided with another circuit which is closed only when relay C is energized, when relay K is deenergized, and when contact 3 of lever L is closed. This latter circuit passes from bus bar 10 through wire 35, front contact 36 of relay C, wire 37, lever light 34, wires 38 and 44, back contact 45 of relay K, wire 46, contact 3 of lever L, and wires 47 and 43 to bus bar 11. When either of these circuits for

lever light 34 is closed, lever light 34 becomes illuminated.

Power-off relay C is provided with a pick-up circuit which is closed when and only when relay K is energized, and which passes from bus bar 10 through wires 26 and 48, front contact 27 of relay K, wires 28 and 29, winding of relay C, and wire 30 to bus bar 11. Power-off relay C is also provided with a stick circuit which is closed when relay C is energized, and which passes from bus bar 10 through wires 26 and 31, front contact 32 of relay C, wires 33 and 29, winding of relay C, and wire 30 to bus bar 11. It will be apparent, therefore, that relay C will normally be energized, but that, in the event of a power failure, that is to say, in the event of an interruption in the supply of current to bus bars 10 and 11 for any reason, this relay will become deenergized, and will subsequently remain deenergized until after relay K has again become energized and closed its front contacts.

With the indication apparatus constructed in this manner, it will be apparent that when relay K becomes deenergized and closes its back contacts due to operation of switch A, one or the other of the circuits previously traced for lever light 34 will become closed, and this light will therefore become illuminated. If, however, relay K becomes deenergized due to a power failure, power-off relay C will then also become deenergized and will interrupt both circuits previously traced for lever light 34, so that when the power is subsequently restored, lever light 34 will remain deenergized in spite of the fact that the back contacts of relay K are then closed for a brief interval of time.

With the indication apparatus constructed in the manner just described, the lever light 34 is supplied with energy from the same source which supplies energy to the indication relay K and the power-off relay C. If desired, however, the lever light 34 may be supplied with energy from a different source of energy from that which supplies energy to the relays K and C without departing from my invention. For example, the indication relay K and the power-off relay C may be supplied with energy from the bus bars 10 and 11 in the manner previously described, while the lever light 34 may be supplied with energy from a transformer T^a through a full wave rectifier F^a as illustrated in Fig. 2. Referring to Fig. 2, as here shown, the primary 27^a of transformer T^a is constantly connected with the terminals X^a and Y^a of a suitable source of alternating current not shown in the drawings, and the secondary 26^a of transformer T^a is constantly connected with the input terminals of rectifier F^a. The output terminals of rectifier F^a, in turn, are connected with wires 43^a and 35^a, which wires correspond to the wires 43 and 35, respectively,

shown in Fig. 1, and are intended to be connected in the circuits previously traced for the lever light 34 in place of the wires 43 and 35. The rectifier F^a may be similar to the rectifier F previously described in connection with Fig. 1. 70

When indication relay K and power off relay C are supplied with energy from the bus bars 10 and 11, as shown in Fig. 1, and the lever light 34 is supplied with energy from the transformer T^a as shown in Fig. 2, the lever light will become illuminated in the manner previously described when relay K becomes deenergized due to operation of switch A, but will remain unilluminated 75 80 when this relay becomes energized due to an interruption in the supply of power to the bus bars 10 and 11 even though transformer T^a is then energized.

Apparatus embodying my invention is particularly suitable for, although in no way limited to, use in interlocking plants in which a large number of switch levers, similar to the lever L are each provided with an indication device which is controlled by a back contact 85 of the indication relay associated with the switch controlled by such lever in the same manner as lever light 34 is controlled by indication relay K, and in which it is desired to supply all of the indication devices with 90 direct current from a source of alternating current through a rectifier. In plants of this type, only a few of the switches are operated at a time, so that normally only a few of the indication relays will be deenergized 95 at one time. It follows, therefore, that normally only a few of the indication devices will be energized, and the load on the rectifier due to the indication devices will therefore normally be small. In the event of a 100 power failure, however, all of the indication relays will become deenergized, and unless means are provided for disconnecting the indication devices from the rectifier under these conditions, then when the power is 105 restored, all of the indication devices will become energized during the interval of time required for the indication relays to pick-up and open their back contacts, and the load on the rectifier due to the indication devices 110 115 will therefore be many times the normal load. This abnormal load on the rectifier due to the indication devices is undesirable, because the rectifier, in order to carry this abnormal load without excessive voltage drop, has to have a considerably larger capacity than would be necessary if the rectifier were only required to carry the normal load due to the indication devices. In accordance with my invention, this abnormal load on the rectifier 120 due to the indication devices may be prevented by providing the interlocking plant with a single power-off relay which is controlled by one or more of the indication relays in 125 the same manner as relay C is controlled by 130

relay K, and which is arranged to disconnect all of the indication devices from the rectifier when this relay becomes deenergized. It will be readily understood from the foregoing description of the operation of the apparatus shown in the drawings, that when an interlocking plant is provided with a power-off relay arranged in this manner, if a power failure occurs, the power-off relay will become deenergized and will subsequently remain deenergized when the power is restored until after the indication relay or relays which control the power-off relay have first become energized, so that none of the indication devices will become deenergized due to the power failure. As a result, the load on the rectifier due to the indication devices will never exceed the normal load, and it follows that the capacity of the rectifier, in so far as the indication devices are concerned, need be only large enough to carry the normal load on the rectifier due to the indication devices.

Although I have herein shown and described only two forms of railway traffic controlling apparatus embodying my invention, it is understood that various changes and modifications may be made therein within the scope of the appended claims without departing from the spirit and scope of my invention.

Having thus described my invention, what I claim is:

1. In combination, a first relay, control means for at times energizing said first relay, a second relay, a pick-up circuit for said second relay including a front contact of said first relay, a stick circuit for said second relay including its own front contact, an indication device, and a circuit for said indication device including a back contact of said first relay and a front contact of said second relay.

2. In combination, a source of current, a first relay, control means for at times supplying current from said source to said first relay, a second relay, means including a front contact of said first relay for at times supplying current from said source to said second relay, means including a front contact of said second relay for at other times supplying said second relay with current from said source, an indication device, and means including a back contact of said first relay and a front contact of said second relay for at times supplying said indication device with current.

3. In combination, a source of current, a relay at times supplied with current from said source, means for at times disconnecting said relay from said source, indication means arranged to be energized when said relay is deenergized, and means operating upon a failure of said source to prevent energiza-

tion of said indication means in spite of deenergization of such relay.

4. In combination, a first source of current, a relay at times supplied with current from said first source, means for at times disconnecting said relay from said source, an indication device, means effective when said relay is deenergized for connecting said indication device with a second source of current, and means operating upon a failure of said first source to prevent energization of said indication device in spite of deenergization of such relay. 70 75

5. In combination, a source of current, a relay, control means for at times supplying current from said source to said relay, indication means normally actuated when said relay is deenergized, and means operating when said relay is connected with said source but deenergized to prevent actuation of said indication means. 80 85

6. In combination, a source of current, a relay at times supplied with current from said source, means for at times disconnecting said relay from said source, an indication device, means normally effective when said relay is deenergized for connecting said indication device with said source, and means operating upon a failure of said source to prevent said indication device from becoming connected with said source in spite of deenergization of said relay. 90 95

7. In combination, a source of current, a relay, control means for at times supplying said relay with current from said source to energize said relay, an indication device, and means for connecting said indication device with said source when said relay becomes deenergized due to operation of said control means but not when said relay becomes deenergized due to a failure of said source. 100 105

8. In combination, a railway traffic governing device, control means for said traffic governing device, a source of current, an indication relay which is normally connected with said source, means controlled by said traffic governing device for at times disconnecting said indication relay from said source, indication means normally arranged to be operated when said indication relay is disconnected from said source, and means operating when said indication relay is connected with said source but deenergized to prevent operation of said indication means. 110 115

9. In combination, a railway traffic governing device, operating mechanism for said device, a manually operable lever for controlling said mechanism, an indication relay, a source of current, means controlled by said traffic governing device for supplying said indication relay with current from said source, means controlled by said indication relay for governing the operation of said lever, a power-off relay, means for supplying said power-off relay with current from said 120 125 130

source in such manner that said power-off relay is normally energized but that in the event of a failure of said source said power-off relay will become deenergized and will 5 subsequently remain deenergized until after said first relay has again been supplied with current from said source, and a device for indicating the condition of said indication relay controlled by said two relays and by 10 said lever.

10. In combination, a railway traffic governing device, operating mechanism for said device, a manually operable lever for controlling said mechanism, an indication relay, 15 a source of current, means controlled by said traffic governing device for supplying said indication relay with current from said source, means controlled by said indication delay for governing the operation of said lever, a power-off relay, means for supplying said power-off relay with current from said source in such manner that said power-off relay is normally energized but that in the event of a failure of said source said power-off 20 relay will become deenergized and will subsequently remain deenergized until after said first relay has again been supplied with current from said source, a device for indicating the condition of said indication relay, and means for supplying said device with current from said source controlled by 25 said power-off relay and by said indication relay.

11. In combination, a railway traffic governing device, operating mechanism for said device, a manually operable lever for controlling said mechanism, and indication relay, a source of current, means controlled by said traffic governing device for supplying said indication relay with current from said source, means controlled by said indication relay for governing the operation of said lever, a power-off relay, means for supplying said power-off relay with current from said source in such manner that said power-off relay is normally energized but that in the event of a failure of said source said power-off relay will become deenergized and will subsequently remain deenergized until after 45 said first relay has again been supplied with current from said source, a device for indicating the condition of said indication relay, and means for supplying said device with current from said source when and only 50 when said indication relay is deenergized and said power-off relay is energized.

12. In combination, a railway traffic governing device, operating mechanism for said device, a manually operable lever for controlling said mechanism, an indication relay, a source of current, means controlled by said traffic governing device for supplying said indication relay with current from said source, means controlled by said indication relay for governing the operation of said 65

lever, a power-off relay, a pick-up circuit for said power-off relay including a front contact of said power-off relay, a stick circuit for said power-off relay including its own front contact, a device for indicating the condition of said indication relay, and a circuit for said device including a back contact of said indication relay and a front contact of 70 said power-off relay.

13. In combination, a railway traffic governing device, operating mechanism for said device, a manually operable lever for controlling said mechanism, an indication relay, a source of current, means controlled by said traffic governing device for supplying said indication relay with current from said source, means controlled by said indication relay for governing the operation of said lever, a power-off relay, means for supplying said power-off relay with current from said source in such manner that said power-off relay is normally energized but that in the event of a failure of said source said power-off relay will become deenergized and will subsequently remain deenergized until after said first relay has again been supplied with current from said source, a device for indicating the condition of said indication relay, and a circuit for said device controlled in part by 80 said lever and including a back contact of 85 said indication relay and a front contact of said indication relay and a front contact of said power-off relay.

In testimony whereof I affix my signature.
RONALD A. McCANN.
